Primary Examiner—Marianne Pandozzi*(74) Attorney, Agent, or Firm*—Armstrong Teasdale LLP**CLAIM**

The ornamental design for a training cup, as shown and described.

DESCRIPTION

FIG. 1 is a perspective view of a training cup showing a first embodiment of our new design;

FIG. 2 is a front elevation thereof;

FIG. 3 is a rear elevation thereof;

FIG. 4 is a right side elevation thereof, the left side elevation being substantially the same as the right side elevation;

FIG. 5 is a top plan view thereof; and

FIG. 6 is a bottom plan view thereof;

FIG. 7 is a perspective view of a training cup showing a second embodiment of our new design;

FIG. 8 is a front elevation thereof;

FIG. 9 is a rear elevation thereof;

FIG. 10 is a right side elevation thereof, the left side elevation being substantially the same as the right side elevation;

FIG. 11 is a top plan view thereof; and,

FIG. 12 is a bottom plan view thereof.
